EDWARD L. ANDERSON AND LOUIS A. ANDERSON, OF ATTLEBORO, MASSACHUSETTS,
ASSIGNORS TO R. & G. COMPANY, OF ATTLEBORO, MASSACHUSETTS.

PENCIL.

1,398,955.

Specification of Letters Patent. Patented Dec. 6, 1921.

Application filed January 17, 1921. Serial No. 437,759.

To all whom it may concern:

Be it known that we, EDWARD L. ANDERSON and LOUIS A. ANDERSON, citizens of the United States, both residing at Attleboro,

5 in the county of Bristol and State of Massachusetts, have invented new and useful Improvements in a Pencil, of which the following is a specification.

This invention relates to certain new and 10 useful improvements in a pencil, and it has for an object to so simplify the construction as to facilitate and expedite the assemblage of the constituent parts thereof during the process of manufacture.

15 The invention also will be found to reside in the salient features of construction and the arrangements and combinations of parts hereinafter specifically described and succinctly claimed, reference being made to the 20 accompanying drawing wherein.

In the drawing:

Figure 1 is a longitudinal sectional view through the improved pencil showing portions of the interior construction in eleva-

25 tion;

Fig. 2 is a detail elevation of the end cap thereof;

Fig. 3 is a similar view of the eraser-holder;

30 Fig. 4 is an elevation of the inner tube; and

Fig. 5 is a similar view of the lead tube.

Referring more in particular to the drawing, the pencil comprises an outer shell 35 or case 1 and an inner tube 2, the latter having its outer end 3 enlarged, for a rotatable fit in the outer end of the case, and also split, as at 4, to provide a resilient extension from the case to frictionally receive the 40 eraser-holder 5 and to be received by the cap 6. In this connection, it may be noted that the cap has an opening in its top through which the eraser 7 or the raised head 8 may project, the latter being suitably 45 finished or set with a jewel.

The inner end of the tube 2 is formed with an abutment 9 against which the washer 10 is disposed, having frictional fit on the tube, and below this washer is a sec- 50 ond washer 11 frictionally engaged in the case but in which the tube is freely rotatable.

On the tube below the washer 11 is a third washer 12 also frictionally held on the tube and projecting beyond the same to snugly receive a disk 13 having an axial opening in

which the upper end of the lead guiding tube 14 is freely supported. The lower end of the lead guiding tube terminates in lead-clamping jaws 15 designed to frictionally hold the lead against retrograde movement, 60 the same co-operating with the tapering lower end of the case 1. The lower end portion of the lead guide tube is forced through a disk or washer 16 having frictional fit in the lower end of the case and against an 65 abutment formed by the tapered end of the case through which the lead projects, whereby the tube is securely held against rotative movement. The pin or plunger 17 for advancing the lead in the tube 14 has a laterally projecting lug 18 which moves in the slot 19 of said tube under the influence of the coiled, thread-forming member 20, the latter having its upper end seated in a second opening or recess in the disk 13 whereby 70 when the inner tube 2 is turned with the fingers the coiled member 20 will also revolve about the lead tube and exert a camming effect on the lug 18.

A retaining clip 21 is also secured in the 80 case by inserting one end through a slot in the wall thereof to lie between the case and the inner tube where it may be fixed as by solder.

In assembling, the washer or disk 16 is 85 first forced into position in the lower end of the case 1 and then the guide tube 14 is forced through the said disk to its proper position, as depicted in Fig. 1. Following this, the lead-advancing follower or plunger 90 17 is dropped in the tube 14 with its lug 18 projecting outwardly through the slot 19, and the coil 20 is then inserted within the case and rotated to bring the plunger into operative position. The operating tube 2, 95 with its assembled washers or collars 10, 11, and 12, is next forced into the case until the tube 14 is engaged in the axial opening of disk 13 and the upper terminal of the coil seated in its opening in the disk. The cap 100 6 and the eraser-holder 5 are then placed on the protruding end of the inner tube 2, and where a clip is utilized the same is mounted following the insertion of the inner tube.

105 Thus, the assembling of the pencil is completed in a very expeditious and easy manner without expensive machine operations. The disk 16 serves to support and sustain the lead tube in proper spaced relation with 110

the case and concentric therewith, the disk 13 coöperating with the former disk in supporting the inner end of said tube. The washer 11 provides a simply constructed retaining means for the operating inner tube, permitting free rotation thereof but preventing lengthwise movement by reason of the abutting washers 10 and 12 on opposite sides thereof. The enlarged end 3 has a rotatable fit in the outer end of the case to provide a rigid structure thereat. By turning the cap, which has frictional connection with the inner tube, the coil member 20 is revolved to correspondingly shift the plunger 17 in the lead tube. This provides an exceedingly simple feed for the lead with few parts to repair or get out of order.

Having thus described our invention, what we claim as new and desire to secure 20 by Letters Patent is:—

1. In a pencil, a case having a tapered end, a disk frictionally engaged within the case and with the tapered end so as to be held by the latter against sliding, an inner 25 tube in the case having an enlarged outer end rotatably engaged with the case and having a reduced inner end forming an abutment, a washer engaging the abutment and frictionally fitted over the reduced end 30 of the tube, a second washer frictionally fitted in the case and rotatably receiving the reduced end of the tube, a third washer frictionally fitted on the tube and projecting beyond same, an apertured disk engaged 35 within the third washer and with the terminal of the reduced end of the tube, a lead-guiding tube received at its upper end in the disk aperture, and lead feeding means including a thread member engaged at one 40 end with the first named disk and at its opposite end being received in an opening provided therefor in the second named disk.

2. A pencil comprising a case, a lead guiding tube secured therein against rotation and provided with a lengthwise slot, a lead-advancing plunger arranged within the tube and provided with a lateral lug operating in the slot, an operating tube rotatable in the case, a pair of relatively spaced collars frictionally fixed on the inner end of the operating tube, a third collar frictionally fixed inside the case between the pair of collars and rotatably receiving the operating tube, and a thread member engaged 50

with the lug and operable by the operating tube.

3. A pencil comprising a case, a lead guiding tube secured therein against rotation and provided with a lengthwise slot, a lead-advancing plunger arranged within the tube and provided with a lateral lug operating in the slot, an operating tube rotatable in the case, a pair of relatively spaced collars fixed on the inner end of the operating tube, a third collar fixed 60 inside the case between the pair of collars and rotatably receiving the operating tube, a disk carried by the inner one of the pair of collars and formed with an opening receiving the inner end of the lead tube, and a 70 coiled member rotatable, about the latter in engagement with the lug and having connection with the disk.

4. In a pencil, a case, a disk frictionally secured therein, a lead tube inserted through 75 and held frictionally by the disk, a plunger movable in the tube and having an outstanding lug operating through a slot longitudinally in the tube, a coiled member encircling the tube and receiving the lug between its coils and an operating device consisting of a tube rotatable within the case and releasably engaged with the adjacent terminal of the coiled member.

5. In a pencil, a case having an abutment 85 therein, a disk frictionally fitted in the case and engaging the abutment, an inner tube in the case rotatably engaged therewith at one end, a washer frictionally fitted in the case, means on the inner tube to engage the 90 washer to limit inward movement of the inner tube, said washer receiving the inner tube to allow the latter to rotate, a washer, frictionally fitted on the inner tube, a disk connected to the last mentioned washer, and 95 lead feeding means including a thread member engaged with the first named disk and with the second named disk so as to be held in place by said disks.

In testimony whereof we have signed our 100 names to this specification in the presence of two subscribing witnesses.
